United States Patent Office

Des. 228,325

Patented Sept. 11, 1973

228,325

SOFA OR SIMILAR ARTICLE

Henning Korch, Lugano, Switzerland, assignor to Burris Industries, Incorporated, Lincolnton, N.C.

Filed Jan. 19, 1972, Ser. No. 219,198

Term of patent 7 years

Int. Cl. D6—02

U.S. Cl. D6—63

FIG. 1 is a front perspective view of a sofa showing my new design;

FIG. 2 is a top plan view thereof; and

FIG. 3 is a rear elevational view thereof.

I claim:

The ornamental design for a sofa or similar article, substantially as shown.
